UNITED STATES PATENT OFFICE.

ARNOLD E. RICHARDS, OF MIDLOTHIAN, MARYLAND.

TIMER.

Application filed December 17, 1924. Serial No. 756,580.

This invention relates to attachment or accessories for use in connection with internal combustion engines and has for its object the provision of a novel timer or distributor in which all the contacts for the respective spark plugs are formed as or provided with rollers successively engageable by a roller which constitutes the grounded terminal, the advantage being that the provision of the rollers will tend to avoid wear and insure proper operation of the device for a longer period of time.

An important object is the provision of a device of this character which will be very simple in manufacture, easy to install, positive in action, efficient and durable in service, and a general improvement in the art.

With the above and other objects and advantages in view, the invention consists in the details of construction to be herein-after more fully described and claimed, and illustrated in the accompanying drawings in which:

Figure 1 is an elevation of a timer constructed in accordance to my invention, the view looking at the inside thereof, a part being broken away and in section,

Figure 2 is a cross sectional view,

Figure 3 is a detail view of the rotatable contact arm, and

Figure 4 is a fragmentary elevation looking at the inside and showing the location of the rollers.

Referring more particularly to the drawings I have shown the device as comprising a cap designated broadly by the numeral 10 and formed of metal. This cap includes a conical end portion 11 and a cylindrical flange portion 12. Secured within the confines of the flange portion 12 are three concentric rings 13, 14 and 15 of suitable insulating material such as fibre or the like. At spaced points, the ring 13 is formed with holes 16 while the rings 14 and 15 are formed with recesses 17 and openings 18, respectively.

Extending radially through the structure thus formed are elongated threaded shanks 19 which pass through suitable bushings 20 of insulating material in the flange portion 12 and which terminate in an enlarged forked head 21 within which are journaled suitable rollers 22 of conducting material. The members 19 constitute terminals and they are equipped with binding nuts 23 whereby the ignition wires may be suitably

connected therewith. The rollers 22 are located within the recesses 17 and project through the openings 18 into the interior of the device in such position as to be disposed in the path of travel of a roller 24 journally mounted within the forked end 25 of an arm 26 which is of angular formation and which is pivoted at 27 upon an extension 28 of a collar 29 mounted on the cam shaft 30 of an engine. The arm 26 is of angular formation and connected with one end thereof is a coil spring 31 which has its other end connected with a second extension 32 on the collar 29 so that the roller 24 will always be urged into engagement with the contact 22 as the arm 25 rotates with the cam shaft.

In the operation, it will be obvious that the spark plug wires are connected with the respective members 19 by means of the binding nuts 23 thereon. The roller 24 constitutes the ground contact and it will be obvious that when the cam shaft is rotating during the running of the motor the engagement of the roller 24 on the arm 25 with the successive rollers 22 will cause the high tension current to be passed through the spark plugs so that a spark will be produced in the usual manner to ignite the explosive charge in the engine cylinders.

From the foregoing description and a study of the drawings it will be apparent that I have thus provided a simply constructed, inexpensive and very efficient device for the purpose specified, the construction and arrangement being furthermore such that in case of wear of the parts they may be readily replaced by new ones so that the length of the life of the device will be greatly increased.

While I have shown and described the preferred embodiment of the invention, it should be understood that I reserve the right to make such changes in the form, construction and arrangement of parts as will not depart from the spirit of the invention or the scope of the subjoined claim.

Having thus described the invention, I claim:

In a timer of the character described, a metallic shell member, a ring of insulating material located within and against the inner periphery of said shell, concentric rings of insulating material located within one another and within the confines of said first named insulating ring, said concentric

rings being formed with recesses and the first named ring being formed with holes at said recesses, contact members including threaded shanks and forks, the forks being located within said recesses and carrying rollers projecting inwardly beyond the inner periphery of the innermost concentric ring member, bushings of insulating material surrounding said shank and fitting within openings in the shell, binding nuts upon said shank engaging upon the outer sides

of said bushings, a shaft journaled at the center of the shell, an angle lever pivotally mounted with respect to the shaft and carrying a roller adapted to coact with said first named rollers, an arm carried by the shaft, and a spring connected with the angle lever and said arm for normally urging the last named roller into cooperative relation to the first named rollers.

20

In testimony whereof I affix my signature.

ARNOLD E. RICHARDS.
